MICROFILM ENLARGER-VIEWER

Joel W. Bravo, Binghamton, N. Y., assignor to General Aniline & Film Corporation, New York, N. Y., a corporation of Delaware

Application June 21, 1957, Serial No. 46,688

Term of patent 14 years

(Cl. D61—1)

FIG.1

FIG.2

FIG.3

Fig. 1 is a front elevational view of the microfilm enlarger-viewer, showing my new design;

Fig. 2 is a side elevational view, the opposite side having substantially the same appearance; and

Fig. 3 is a perspective view of the same.

The back, not shown, is substantially plain. A portion of the drawing figures is diagonally lined to indicate transparency.

I claim:

The ornamental design for a microfilm enlarger-viewer, substantially as shown and described.
